Attorney

UNITED STATES PATENT OFFICE

CARL ZORN, OF MUNICH, GERMANY

AUTOMATICALLY FILLING FOUNTAIN PEN

Application filed February 10, 1932, Serial No. 592,104, and in Germany February 11, 1931.

This invention relates to an automatically filling fountain pen with a rubber hose for the ink located in the tubular holder and exerting a suction effect, and with a flexible 5 blade spring, one end of which spring is adapted to be shifted in axial direction by means of a rotatable handle for bending the spring prior to the filling.

This invention has for its object, to enable 10 the operation of the blade spring by the simplest possible construction for right handed as well as left handed people in any easy manner and so that the blade spring is automatically secured against accidental operation. 15 With this object in view a handle is provided adapted to be turned and consisting of a ring pushed over the holder and connected with the axially shiftable end of the blade spring by means of a transverse pin on 20 one element guided in an inclined groove of the other element.

An embodiment of the invention is illustrated by way of example in the accompanying drawing in which:—

25 Fig. 1 shows the fountain pen in elevation. Fig. 2 is a longitudinal section on line 2—2 of Fig. 1.

Fig. 3 shows in elevation the tubular body 30 of the fountain pen.

Fig. 4 is a section through the body on line 4—4 of Fig. 3.

Fig. 5 is a cross section on line 5—5 of 35 Fig. 3.

Fig. 6 shows in elevation the turnable handle with inclined guide groove directed in opposite direction as in Fig. 1.

Fig. 7 shows in elevation the turnable handle with an angular guide groove.

40 Fig. 8 is a vertical section through the turnable ring or handle.

Fig. 9 shows in elevation a blade spring as used in connection with the turnable ring shown in Fig. 8.

45 In the sleeve or body *b* of the fountain pen a rubber hose *c* is located, which is known per se and serves for sucking in the ink. This rubber hose *c* is pushed over the rear end *f* of the head piece *a*, *g*, *h* of the fountain pen.

50 The open end of the rubber hose *c* is simply

pulled over the tubular socket *h* of the head piece.

In the sleeve *b* a blade spring *e* is located at the side of the rubber hose *c*, said spring bearing at the front end against the screw threaded portion *g* of the head piece. The spring has at its rear end a coupling projection *n*. This projection *n* engages with an inclined guide *m* of a turnable ring *l* located 55 between the sleeve *b* and the rear cap *i*. The inclined guide consists either of a slot or of a groove. The rear portion of the blade spring *e* carrying the coupling projection *n* is located, axially shiftable, in an external vertical groove *u* of the sleeve *b* and extends into 60 this groove from the interior of this sleeve through an aperture *k*.

The inclined guide groove *m* in the turnable ring *l* extends from right to left for right handed people, as shown in Fig. 1, and from 65 left to right for left handed people as shown in Fig. 6. If one and the same fountain pen has to be used by right handed as well as by left handed people the inclined guide *m* has 70 two arms inclined in opposite directions as shown in Fig. 7. The apex *p* of the angle is formed by the two grooves forming the point for the inoperative position of the coupling projection *n*. In order to ensure a uniform 75 compressing of the rubber hose a pressure bar *d* may be provided acting upon the blade spring *e*.

As shown in Fig. 6, the guide *m* consisting 80 of a slot can be covered by a protecting ring *r* as shown in Fig. 6, this ring being preferably 85 arranged between milled beads *s* on the upper and lower ends of the turnable ring *l*. The inclined guide *m*, instead of being arranged in the turnable ring *l*, may be arranged, as 90 shown in Fig. 9 in an enlarged portion *t* of the blade spring *e*, the coupling projection *n* being then arranged, as shown in Fig. 8, in the turnable ring *l*.

If the turnable ring *l* is turned from right 95 to left, from the position shown in Fig. 1 towards the coupling position *n*, this coupling projection is pushed forward and shifts forward the rear end of the blade spring *e* so that the compressing of the hose *c*, necessary 100 for the automatic filling, is effected by

the bending of the blade spring *e*. This curved position of the blade spring is indicated in Fig. 2 in dash lines.

If the turnable ring *l*, after the point *q* of the holder has been dipped into an inkpot, is released again, this ring *l* is automatically returned into its initial position by the expanding blade spring *e*, the rubber hose *c* being thus liberated to expand and to suck in the ink.

10 I claim:

1. An automatically filling fountain pen, comprising in combination a tubular body, a head piece on the front end of said body, a closing cap on the rear end of said body, a rubber hose in said body, a blade spring at the side of said rubber hose, a turnable ring between the rear end of said body and said cap, and a coupling device between said turnable ring and said blade spring consisting of a coupling projection on one of said elements and of an inclined guide on the other of said elements.

2. An automatic fountain pen as specified in claim 1, in which the coupling projection is arranged on the rear end of the blade spring and an angular guide is arranged in the turnable ring so that the device can serve as well for right handed as for left handed people.

3. An automatically filling fountain pen as specified in claim 1, comprising in combination with the turnable ring having an inclined guide slot, a protecting ring turnable on said turnable ring designed to cover said guide slot.

In testimony whereof I affix my signature.
CARL ZORN.
